UNITED STATES PATENT OFFICE.

WALTER GROTHE, OF FREMONT, OHIO, ASSIGNEE, BY MESNE ASSIGNMENTS, TO
NATIONAL CARBON COMPANY, INC., A CORPORATION OF NEW YORK.

ELECTRIC BATTERY.

1,276,754.

Specification of Letters Patent. Patented Aug. 27, 1918.

Application filed February 5, 1916. Serial No. 76,235.

To all whom it may concern:

Be it known that I, WALTER GROTHE, a citizen of the United States, residing at Fremont, in the county of Sandusky and State of Ohio, have invented a certain new and useful Improvement in Electric Batteries, of which the following is a full, clear, and exact description.

This invention relates to primary batteries and consists in novel arrangements for supporting the electrode elements within the containers.

Referring to the drawings, Figure 1 is an elevation of the electric cell embodying my improvement, the glass jar and cover being shown in section.

Fig. 2 is a transverse section of the electrode assembly taken on the line A--A of Fig. 1.

Fig. 3 is a partial sectional elevation of the electrode assembly taken on the line B--B of Fig. 2.

Fig. 4 is a perspective view of the insulating spool.

Fig. 5 is a perspective of the supporting yoke.

Fig. 6 is a perspective view of the clip.

The supporting member for the electrodes consists of a flanged yoke 1 having depending ends 3 which may conveniently be stamped from sheet metal. A suspending bolt or rod passes through a hole in the yoke and is riveted therein by upsetting or peening over the end so that the yoke is rigidly clamped between washer 5 and shoulder 6 of the rod. The rod, however, may be secured to the yoke in other ways.

A spool 6 of porcelain or other insulation, consisting of a non-circular shank 7 with two non-circular heads or flanges 8, is arranged to be clamped against the yoke 1 by a clip 9 in such a way that the yoke fits snugly in between the heads of the spool. The shank and heads are preferably of triangular shape and the corners are preferably chamfered at 10 and 10' to prevent breakage. The clip 9 is shaped to fit inside the side flanges 11 of the yoke between the depending ends 3. This clip has a depending V-shaped

portion 11' adapted to receive the shank portion of the spool and prevent the same from turning or sliding lengthwise of the yoke. The ends 12 of the clip are bent at right angles as shown, and may be slotted at 13 to make them more flexible.

A perforated container 14, closed on all sides excepting the top, is adapted to be clamped between the depending ends 3 of the yoke and the ends 12 of the clip. This container is preferably made from a single sheet of perforated sheet metal cut in such a way as to fold into the desired shape, with staples or other fasteners to hold the same together in much the same manner as paper boxes are made.

The two zinc electrodes 15, 15 are preferably made with a frame portion 16 around the edge, with one or more strengthening ribs 17 extending from the base to the thickened portion 18 at the top of the electrode. The ribs and frame are preferably made on one side only, leaving the other side with a smooth surface which should be placed next to the perforated container. The thickened portion 18 of the zines is recessed at 19 to receive the heads 8 of the insulating spool, and has holes 20 to receive the clamping belt hereinafter referred to.

To assemble the parts the insulating spool 6 is placed in the depending V-shaped portion 11' of the clip 9 and is rigidly clamped in position by screws 22 which pass through the yoke and thread into holes in the clip. When placed in this position the flanges on the spool extend up along the side flanges 11 of the yoke and transverse movement of the spool is prevented. The container, previously filled with a depolarizer 22' such as flaky copper oxide for example, is then clamped between the ends of the clip and yoke by screws 21 which may thread into the ends of the clip.

After assembling the copper oxide container, as explained above, a zinc electrode is placed on each side thereof, with the recess 19 fitting over one of the heads 8 of the spool. These recesses are shaped similarly to the heads, so that the zines cannot turn around the axis of the spool. A bolt 23 extending through the hole 24 of the spool and the hole 20 of the zinc, clamps the zines rigidly to the remaining parts of the electrode assembly.

An insulated terminal member 26 is electrically connected to the zinc electrodes, preferably by coiling one end around bolt 23 inside of a cupped metallic washer 27, and clamping this securely against the interposed conducting washer 25.

To suspend the assembly in the jar 28 the

rod 4 is passed through cover 23' and secured in place by a nut 29 which binds the cover tightly against shoulder 29' on the suspending rod. One or more winged nuts 30 on this bolt serve to clamp a conducting wire to the depolarizing element. The insulated terminal 26 passes through a hole in the cover and serves for the other terminal of the battery.

16 When the cell is to be used it will of course be filled with a suitable electrolyte such as sodium hydroxid solution, if copper oxid is used as the depolarizing material.

Having described my invention, what I claim is:

1. In electric batteries, a flanged yoke having depending ends, an insulating electrode support beneath said yoke and extending transversely thereacross, a clip having depending ends and adapted to clamp the support to the yoke, a container for depolarizing material secured between the depending ends of said clip and yoke, and a rod attached to the yoke above said support.
2. In electric batteries, a flanged yoke having depending ends, an insulating electrode support beneath said yoke and extending transversely thereacross, a clip fitting between said flanges and adapted to clamp said support thereagainst, said clip having de-

pending ends lying between the depending ends of said yoke, a container for depolarizing material having sides clamped between adjacent depending ends of said yoke and clip, and a rod attached to the yoke above said support.

3. In electric batteries, a flanged yoke having depending ends with a hole therethrough, an insulating electrode support beneath said yoke and extending transversely thereacross, a clip between the flanges of the yoke adapted to clamp the support thereagainst, said clip having depending ends with a threaded hole, a container for depolarizing material having sides fitting between the depending ends of the yoke and clip and screws passing through the holes in the depending ends of the yoke and into the threaded ends of the clip to clamp the said container in position.

4. In electric batteries, a supporting yoke, a rod having two shoulders thereon, one end of said rod passing through the yoke and being upset to clamp the yoke against the one of said shoulders, a battery jar, a cover therefor, and means to clamp the cover against the other of said shoulders.

In testimony whereof, I hereto affix my signature.

WALTER GROTH.
